(Cl. D59—2)

To all whom it may concern:

Be it known that I, Kenneth C. Hamilton, a citizen of the United States, residing at Milwaukee, in the county of Milwaukee and State of Wisconsin, have invented a new, original, and ornamental Design for a Napkin or Similar Article, of which the following is a specification, reference being had to the accompanying drawing, forming a part thereof.

The figure of the drawing is a face view of a quarter-section of a napkin embodying my new design, which design is repeated symmetrically in each of the other three-quarters of the napkin. While my new design is shown in the drawing as delineated on a napkin, it is contemplated that the same may be applied to other similar articles without departing from the spirit of the invention.

I claim:

The ornamental design for a napkin or similar article, substantially as shown and described.

KENNETH C. HAMILTON.
